UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 24, 1923. Serial No. 659,102.

My invention relates to railway traffic controlling apparatus, and particularly to train governing apparatus arranged to be controlled in part at least by a despatcher or other authorized official. More particularly my invention relates to the trackway portion of such apparatus.

I will describe one form and arrangement of apparatus embodying my invention, and will then point out the novel features thereof in claims.

In the accompanying drawings, Figs. 1^a and 1^b, when placed end to end with Fig. 1^a to the left, form a diagrammatic view showing one form of apparatus embodying my invention.

Similar reference characters refer to similar parts in both figures of this drawing.

Referring to this drawing, the reference characters 1 and 1^a designate the track rails of a single track railway over which traffic normally moves in both directions. The stretch of track shown in the drawing is provided with two passing sidings F and F^a, respectively, located at the left hand end and right hand end of the stretch. Only the right hand half of siding F is shown in the drawing but it is understood that the apparatus associated with the two sidings F and F^a is identical. The track rails 1 and 1^a are divided, by means of insulated joints 2-2, into a plurality of successive track sections A-B, B-C, C-D, D-E, E-Q, etc., it being obvious that any reasonable number of such sections may occur between two consecutive passing sidings, depending upon the actual conditions.

Traffic from right to left over the stretch of track shown in the drawing is controlled by signals S¹² and S² located adjacent points Q and A, respectively. Traffic from left to right over this stretch is governed by a signal S¹¹ located adjacent point E and another similar signal not shown in the drawing but located adjacent the left hand end of siding F.

As shown in the drawing each of the signals S², S¹¹ and S¹² is a "color light signal" and is provided with three signal lamps 4, 5 and 6, adapted, when lighted, to project

a beam of red light, of yellow light or green light, respectively, and thus display a stop, a caution or a proceed indication in accordance with standard signaling practice, though this particular form of signal is not essential to the present invention.

Each end of each section is provided with a source of track circuit such as a secondary 7 of a track transformer designated in general by the reference character T and each of which transformers is specifically designated by an exponential character. Each such secondary 7 is constantly connected across the rails of the associated section one adjacent each end thereof, and the primary 8 of each transformer T is at times supplied with alternating current as will appear hereinafter. Interposed between one rail 1 and the secondary 7 of each track transformer T is an impedance 9, one function of which is to limit the output of the transformer when its terminals are short circuited by the wheels and axles of a train occupying the associated section.

Each section is provided with two track relays, one located adjacent each end thereof, and designated by the reference character R with an exponent corresponding to the location. Each of these relays R is provided with two windings 15 and 20, one of which, 20, is constantly supplied with alternating current. For example, relay R⁷ is provided with a circuit which passes from the secondary of line transformer H⁰, through wire 21, winding 20 of relay R⁷, and wires 22, 23 and 24 back to transformer H⁰. A line transformer designated by the reference character H with an exponent corresponding to the location is provided for each section. The primary of each such transformer H is constantly supplied with alternating current from an alternator O over line wires 3 and 3^a. The winding 15 of one of the track relays R associated with each section is constantly connected across the rails adjacent one end of the section and the winding 15 of the other such relay is arranged to be at times connected across the rails adjacent the other end of the section.

Associated with each track relay R is a

line relay designated by the reference character W with an exponent corresponding to the location. Referring particularly to line relay W^5 , this relay is provided with a circuit which passes from the secondary of transformer M^c , whose primary is constantly supplied with alternating current from transformer H^c , through wire 25, front contact 26 of line relay W^7 , wire 27, front contact 30 of track relay R^8 , wire 31, back contact 32 of a "stick" relay K^{10} , wire 33, front contact 34 of track relay R^5 , wire 35, winding of relay W^5 and wires 36, 37 and 38 back to transformer M^c . This circuit is provided with a branch which passes from wires 25 and 29, through front contact 28 of "stick" relay K^7 , and back to wire 27. It is therefore evident that relay W^5 is energized only when relays W^7 , R^5 and R^8 are energized and relay K^{10} is de-energized, but that when relay K^7 is energized, the closing of its front contact 28 removes relay W^7 from the control of relay W^5 . Line relays W^8 , W^7 and W^6 are provided with circuits exactly like those just traced for relay W^5 .

Line relay W^9 is provided with a circuit which passes from the secondary of line transformer H^q through wires 39 and 40, back contact 41 of relay I^{13} , wire 42, front contact 43 of track relay R^2 , wire 44, back contact 45 of relay G^2 , wire 46, front contact 47 of track relay R^{11} , wire 48, front contact 49 of track relay R^4 , wire 50, back contact 51 of relay K^6 , wire 51^a, front contact 52 of track relay R^1 , wire 53, winding of relay W^9 and wires 54, 60, 60^a and 55 back to transformer H^q . It follows that relay W^9 is energized only when relays R^2 , R^{11} , R^4 and R^1 are energized and relays I^{13} , G^2 and K^6 are de-energized. An auxiliary circuit is also provided for relay W^9 which passes from transformer H^e through wires 56 and 57, front contact 58 of stick relay K^{11} , wire 59 back to wire 48, thence as before to wires 54 and 60 back to transformer H^e . It will therefore be clear that when stick relay K^{11} is energized, as by a train moving from left to right into section E-F at point E, the closing of front contact 58 on relay K^{11} removes relays R^{11} , R^2 , G^2 and I^{13} from the control of relay W^9 . Relay W^{10} at point B is provided with circuits similar to those just traced for relay W^9 , the control for relay W^{10} extending beyond the limits of the drawing.

Relays W^2 and W^{11} associated with siding F^a and line relay W^{12} associated with siding F are all of the polarized, three-position type. Each of these relays is provided with two windings 16 and 17 the latter of which is constantly connected with a source of energy. Thus, referring particularly to relay W^2 a circuit is provided, passing from transformer H^q through wires 39 and 61, winding 17 of line relay W^2 and wires 62,

63 and 55 back to transformer H^q . The relay is therefore responsive to reversals of the relative polarity of the current supplied to winding 16. One path for this current is from left hand terminal of the secondary of transformer M^p , through wire 64, front contact 65 of line relay W^6 , wire 66, front contact 67 of line relay W^6 , wire 68, back contact 69 of stick relay K^6 , wire 70, front contact 71 of track relay R^9 , wire 72, back contact 73 of relay I^4 , wire 74, front contact 75 of track relay R^4 , wire 76, front contact 77 of track relay R^{11} , wire 78, back contact 79 of relay G^{11} , wire 80, back contact 81 of relay K^{11} , wire 82, front contact 83 of track relay R^2 , wire 84, winding 16 of line relay W^2 , wires 62, 63, 55, 60^a, 60, 54 and 85, front contact 86 of line relay W^6 and wire 87 back to transformer M^p . The primary of transformer M^p is constantly supplied with alternating current from transformer H^p . It is clear that this circuit can be closed only when relays W^6 , R^9 , R^4 , R^{11} and R^2 are energized and relays K^6 , I^4 , G^{11} and K^{11} are de-energized, under which conditions the current supplied to relay W^2 is of what I shall term "normal relative polarity", and the contact fingers of this relay are swung toward the right. When relay W^6 is de-energized, however, as by a train moving from right to left in section C-D, relay K^6 , as will appear hereinafter, is energized and the circuit for relay W^2 now passes from the right hand terminal of the secondary of transformer M^p , through wire 87, back contact 65 of line relay W^6 , wire 88, front contact 69 of stick relay K^6 , wire 70, thence as before to wire 85 then over back contact 86 of line relay W^6 , and wire 64 back to transformer M^p . When this circuit is closed relay W^2 is supplied with current of what I shall term "reverse relative polarity" and the contact fingers thereof are swung toward the left. If for any reason the energizing circuits for this relay are interrupted the supply of current to winding 16 of relay W^2 is discontinued and the contact fingers thereof assume an intermediate position. It will therefore be clear that armatures 65 and 86 of line relay W^6 operate as a pole changer for reversing the relative polarity, and hence the direction of energization, of relay W^2 . Relays W^{11} and W^{12} are controlled in exactly the same manner as relay W^2 , although the control of these two relays extends beyond the limits of the drawing.

Associated with line relay W^2 is a repeater relay G^2 which is controlled by a circuit passing from transformer H^q through wires 39 and 89, front contact 90 of relay I^{13} , wire 91, normal or reverse contact 92 of line relay W^2 , wire 93, winding of relay G^2 , and wires 94, 63 and 55 back to transformer H^q . It is plain that this circuit is closed only when relay I^{13} is energized and relay W^2 is ener-

gized in either direction. Repeater relays G^{11} and G^{12} , controlled in exactly the same manner as repeater relay G^2 , are provided for line relays W^{11} and W^{12} , respectively.

Reference has been made to stick relay K^6 associated with line relay W^6 . This relay is provided with a pickup circuit which passes from transformer H^D , through wires 95 and 96, back contact 97 of line relay W^6 , wire 98, back contact 99 of track relay R^9 , wire 100, back contact 101 of track relay R^6 , wire 102, front contact 103 of relay W^6 , wire 104, winding of relay K^6 , and wires 105, 23 and 107 back to transformer H^D . This circuit is closed only when relays R^9 , R^6 and W^6 are de-energized and relay W^6 is energized. A stick circuit is also provided which passes from transformer H^D , through wires 95 and 110, back contact 111 of track relay R^6 , wire 112, front contact 109 of relay K^6 , wire 108, and wires 105, 23 and 107 to transformer H^D . It will thus be plain that if a train moves from left to right through section C—D relay W^6 will be de-energized and that relay K^6 will therefore not pick up; but that if a train moves from right to left relays R^9 and W^6 will be de-energized and entrance of the train into section C—D at point D will de-energize relays R^6 and W^6 , but relay W^6 is a slow-releasing relay and stick relay K^6 therefore has time enough to close its front contacts before the front contacts of relay W^6 are opened following the de-energization of that relay. Stick relay K^6 is then held in its energized position over its own front contact as long as track relay R^6 is de-energized by a train occupying any portion of section C—D.

The control of each stick relay K^{10} , K^5 , K^8 , K^7 and K^9 is analogous to the control of stick relay K^6 . The remaining stick relays K^2 , K^{11} and K^{12} are controlled in part by the associated repeater relays G . Referring particularly to relay K^2 , its pick-up circuit starts with transformer H^Q , and passes through wires 39 and 113, back contact 114 of track relay R^2 , wire 115, front contact 116 of relay G^2 , wire 117, winding of relay K^2 , and wires 118, 63 and 55 back to transformer H^Q . It will be plain that this circuit is closed only when relay R^2 is de-energized and relay G^2 is energized. The retaining, or stick circuit for the relay K^2 passes from transformer H^Q , through wires 39 and 113, back contact 114 of track relay R^2 , wires 115, front contact 120 of relay K^2 , wire 119, winding of relay K^2 , and wires 118, 63 and 55 back to transformer H^Q . It will thus be clear that the operation of the relay K^2 is similar to that described for relay K^6 .

It will be observed that certain of the stick relays K are provided with repeater relays designated by the reference character P and having an exponent corresponding to the location. For example, relay P^6 is included

in a circuit passing from transformer H^C , through wires 21 and 121, front contact 122 of stick relay K^7 , wire 123, back contact 124 of track relay R^7 , wire 125, back contact 126 of stick relay K^8 , wire 127, back contact 128 70 of track relay R^6 , wire 129, winding of relay P^6 and wires 130, 23 and 24 back to transformer H^C . It follows that relay P^6 normally repeats the condition of relay K^7 but that the circuit passes over a back contact 126 75 of the opposing stick relay K^8 , thus checking the position of that relay. The control of relay P^8 is precisely similar to that of relay P^6 .

Relay P^4 is controlled by a circuit similar to that just described for relay P^6 except that it also includes a front contact 65 of line relay W^6 . Repeater relays P^3 and P^{13} are controlled in exactly the same manner as repeater relay P^4 .

Relay P^{11} is provided with a circuit which passes from transformer H^Q through wire 39, front contact 106 of relay K^2 , wire 131, back contact 83 of track relay R^2 , wire 82, back contact 81 of stick relay K^{11} , wire 80, back contact 79 of repeater relay G^{11} , wire 78, back contact 77 of track relay R^{11} , wire 132, winding of relay P^{11} and wires 133, 134, 60^a and 55 back to transformer H^Q . Relay P^4 is energized, therefore, only when relays R^2 , R^{11} , G^{11} and K^{11} are de-energized and relay K^2 is energized.

Certain of the track transformers, as T^{12} , T^{10} , T^5 , T^7 , T^9 and T^2 have their primary windings normally connected with a source of alternating current which connection is at times interrupted. Referring particularly to transformer T^9 , this transformer is provided with a circuit passing from transformer H^D , through wires 95 and 135, back contact 136 of stick relay K^9 , wire 137, primary winding 8 of track transformer T^9 , and wires 138 and 107 back to transformer H^D . It is evident that section D—E is supplied with track circuit current by transformer T^9 as long as relay K^9 is de-energized.

The remaining track transformers are each normally disconnected from the associated section but are arranged to be at times connected therewith. For example, track transformer T^8 is provided with a circuit passing from transformer H^C , through wires 21 and 139, front contact 140 of relay P^8 , wire 141, primary winding 8 of track transformer T^8 , and wire 24 back to transformer H^C . It is clear that section B—C is supplied with track circuit current by transformer T^8 only when relay P^8 is energized; but relay P^8 is energized only when relay K^8 is energized and the energization of relay K^8 disconnects energy from transformer T^8 which normally feeds the other end of section B—C. It therefore follows that each section is supplied with track circuit current from the track transformer located at one end or the

125 130

other of the section depending upon traffic conditions.

The winding 15 of certain of the track relays such as R^{12} , R^{10} , R^5 , R^7 , R^9 and R^2 is constantly connected across the rails of the associated section. Referring particularly now to section B-C, track relay R^5 has its winding constantly connected across the rails adjacent the left hand end of this section. But transformer T^5 , connected at the same point, is normally energized and to protect the relay against over-energization, I interpose an impedance 14 between winding 15 and one rail 1 of the section B-C. When section B-C is supplied with track circuit current from the right hand end, however, this impedance is not necessary, and under this condition a low resistance shunt circuit is provided around this impedance from rail 1 through wire 142, front contact 143 of stick relay K^5 , and wire 144 back to the right hand side of winding 15 of track relay R^5 .

The remaining track relays are normally connected across the rails but are arranged to be disconnected therefrom when the track transformer located at the same end of the associated section is energized. For example, winding 15 of relay R^8 is provided with a circuit which passes from rail 1 of section B-C, through wire 145, winding 15 of track relay R^8 , wire 146, back contact 147 of relay P^8 , and wire 148, back to rail 1^a of section B-C.

Each signal S is controlled by its associated line relay W and repeater relay G in the following manner: Referring particularly to signal S^2 , the stop, or red lamp 4 of this signal is provided with a circuit which passes from the secondary of a lighting transformer J^0 , whose primary is constantly supplied with alternating current from transformer H^0 , through wire 245, back contact 246 of relay G^2 , wire 247, lamp 4 of signal S^2 , and wire 248 back to transformer J^0 . This circuit is closed when relay G^2 is de-energized so that lamp 4 is normally energized and signal S^2 therefore normally displays a stop indication. The caution circuit for signal S^2 passes from transformer J^0 through wire 245, front contact 246 of relay G^2 , wire 149, reverse contact 150 of relay W^2 , wire 152, caution lamp 5 of signal S^2 , and wire 248 back to transformer J^0 . This circuit is closed only when relay G^2 is energized and relay W^2 is energized by current of reverse relative polarity in which case lamp 5 is lighted and signal S^2 displays a caution indication. The proceed circuit for this signal passes from transformer J^0 through wire 245, front contact 246 of relay G^2 , wire 149, normal contact 150 of relay W^2 , wire 151, proceed lamp 6 of signal S^2 , and wire 248 back to transformer J^0 . This circuit is closed only when relay G^2 is energized and relay W^2 is energized by current of normal

relative polarity in which case lamp 6 is lighted and signal S^2 displays a proceed indication.

Traffic through the stretch of track shown in the drawing is controlled, as has been before stated, from a central point which is usually the office of a train despatcher from which office each signal can be controlled at the will of the operator dependent upon traffic conditions in that portion of track which is governed by the signal. This control is effected by means of selectors located at intervals along the trackway, each of which is designated by the reference character X with an exponent corresponding to the location. As here shown, one such selector is located at each end of each passing siding, but this particular location and arrangement of selectors may be varied to suit the conditions met with in each installation. These selectors are controlled in any suitable manner from the despatcher's office through the medium of a pair of line wires 152 and 152^a. Each selector in the form here shown comprises two contacts 153-154 and 153-155, both of which are normally open. For purposes of the present invention it is sufficient to state that any contact in any selector can be closed for a short interval of time by the manipulation of the proper controlling apparatus in the despatcher's office. One form of apparatus which will function in this manner is illustrated and described in United States Letters Patent No. 1,355,055, granted to R. C. Leake on Oct. 5, 1920, and in Geer and Leake Patent No. 1,118,120 referred to therein, although numerous other forms of apparatus are commercially available and may be used equally well.

When the despatcher wishes to cause signal S^2 to display a proceed indication, he operates suitable apparatus in the despatcher's office for closing contact 153-155 of selector X^0 which closes a circuit from transformer H^0 , through wire 39, contact 153-155 of selector X^0 , wire 156, normal or reverse contact 157 of line relay W^2 depending on the direction of energization of that relay, wire 158, winding of relay I^{12} and wires 159, 54, and 55, back to transformer H^0 . This circuit is closed only when relay W^2 is energized and contact 153-155 of selector X^0 is closed, under which conditions relay I^{12} is energized and is therefore caused to close its front contacts. After a predetermined short interval of time, contact 153-155 of selector X^0 again opens but relay I^{12} is not de-energized, its retaining circuit now being closed which circuit passes from transformer H^0 through wires 39 and 160, back contact 161 of relay I^{12} , wire 162, front contact 163 of relay I^{12} , wire 164, winding of relay I^{12} and wires 159, 54 and 55 back to transformer H^0 . By operating selector X^0

in this manner the despatcher energizes relay I^{13} which closes the circuit for relay G^2 over its front contact and therefore causes signal S^2 to display a proceed indication if sections $E-Q$, $D-E$ and $C-D$ are unoccupied by a train moving toward the left, and a caution indication if sections $E-Q$ and $D-E$ are unoccupied and sections $C-D$ is occupied by a train moving toward the left.

10 If a train moving toward the right occupies any portion of the track to the left of point Q , signal S^2 will continue to display a stop indication since relay I^{13} will not pick up, its circuits being broken at contact 157 of relay W^2 .

If the despatcher wishes to return the signal S^2 to stop and the apparatus associated therewith to its normal condition, he may do so by closing contact 153-154 of selector X^0 . This operation completes a circuit passing from transformer H^0 through wire 39, contact 153-154 of selector X^0 , wire 165, winding of relay L^{13} , and wires 166, 54, and 55 back to transformer H^0 . When this circuit is closed relay L^{13} is energized, thus breaking at back contact 161 thereon, the retaining circuit for relay I^{13} which thereupon becomes de-energized. After a short interval of time contact 153-154 of selector X^0 opens, thus returning the apparatus to its normal condition. Signals S^{11} and S^{12} are controlled by the associated selectors X^B and X^A respectively exactly as signal S^2 is controlled by its associated selector X^0 .

35 Means are also provided for each section for supplying to the rails in parallel a current which I shall hereafter term a "local" current. This current is supplied by means of double secondary local transformers each 40 designated by the reference character N with an exponent corresponding to the location. For this purpose I connect an impedance 10 across the rails adjacent the left hand end of each section, a similar impedance 13 adjacent the right hand end of each section, and two similar impedances 11 and 12 at 45 intermediate points in the section.

Traffic moving from right to left through section $C-D$ is controlled by a local circuit 50 which may be traced from secondary 18 of local transformer N^C through wire 167, front contact 168 of line relay W^8 , wire 169, back contact 170 of stick relay K^7 , wire 171, back contact 172 of repeater relay P^6 , wire 173, impedance 13 in section $C-D$, through both 55 rails of the section in parallel to impedance 10, thence through wires 174 and 175 front contact 176 of relay W^8 , and wire 177 back to secondary 18 of transformer N^C , the primary of which is constantly supplied with 60 alternating current from transformer H^C .

This circuit is closed only when relay W^8 is energized and relays K^7 and P^6 are de-energized, under which condition the rails 65 of section $C-D$ are supplied with local cur-

rent of what I shall term "normal relative polarity". If, however, section $B-C$ is occupied by a train moving toward the left the consequent de-energization of line relay W^8 will close a circuit from secondary winding 18 of local transformer N^C through wire 167, back contact 168 of relay W^8 , wire 178, front contact 179 of relay K^8 , wire 180, impedance 11 in section $C-D$, through both rails of the section in parallel to impedance 13, thence by wires 173, back contact 172 of relay P^6 , wire 171, back contact 170 of relay K^7 , wire 169, back contact 176 of relay W^8 and wire 177 back to winding 18 of local transformer N^C . This circuit is closed only 70 when relays W^8 , K^7 and P^6 are de-energized and relay K^8 is energized, under which condition local current of what I shall term "reverse relative polarity" is supplied to the rails of section $C-D$ between impedances 85 11 and 13. It should be particularly pointed out that the circuit just traced is complete only when the train occupying section $B-C$ is moving toward the left for if this train were moving toward the right relay K^8 90 would be de-energized, thus opening the local circuit at its front contact 179. Traffic moving from right to left through sections $B-C$ and $D-E$ and from left to right through sections $A-B$ is supplied with local 95 current in exactly the same manner as just described for section $C-D$.

Traffic moving from left to right through section $C-D$ is provided with local current from secondary winding 19 of local transformer N^D over circuits similar to those described above except that relays K^7 and P^6 are now energized and the circuit therefore passes over front contacts 170 and 172 of these two relays, respectively, instead of 100 their back contacts, to wire 171. Similar local circuits are provided for traffic moving from left to right through section $B-C$. Similar local circuits are provided for traffic from left to right through section $D-E$ and for traffic from right to left through section 110 $A-B$, with the single exception that the pole-changing or reversing of the local current is accomplished, in these two latter cases, by means of the repeater relays G located at 115 the exit ends of the sections instead of by means of line relays W .

Section $E-Q$ is provided with a local circuit which passes from winding 19 of local transformer N^E , through wire 181, impedance 13 in section $E-Q$, through both rails of the section in parallel to impedance 10, thence by wire 182, front contact 183 of stick relay K^{11} , wire 184, back contact 185 of relay P^{11} , wire 186, back contact 187 of relay K^2 , wire 188, front contact 189 of track relay R^{13} , and wire 190, back to winding 19 of local transformer N^E . This circuit is closed only when relays R^3 and K^{11} 125 are energized and relays K^2 and P^{11} are de- 130

energized, under which conditions traffic moving from left to right through section E—Q is supplied with local current of normal relative polarity. For traffic moving from right to left through section E—Q the local circuit passes from secondary 19 of local transformer N^E , through wire 191, front contact 192 of track relay R^4 , wires 193 and 182, impedance 10 in section E—Q, 10 through both rails of the section in parallel to impedance 13, thence through wire 181, front contact 187 of relay K^2 , wire 186, front contact 185 of section P^{11} , and wire 194 back to winding 19 of local transformer N^E . This 15 circuit is closed only when relays R^4 , K^2 and P^{11} are energized, under which condition the rails of section E—Q are supplied with local current of normal relative polarity. It will be noticed that no means are 20 provided for supplying a local current of reverse relative polarity to this section and that the control of the local current is extended into the section next in advance for train movements in either direction. For example, a train occupying either section E—Q or section D—E will operate to prevent the 25 supply of local current to a train moving through section E—Q from right to left. It will also be noticed that the local circuits 30 extend the entire length of the section and that the intermediate impedances 11 and 12 have been omitted.

The apparatus associated with the portion 35 of track to the right of point Q is similar to the apparatus associated with the left hand end of section A—B, and the apparatus located to the left of point A is similar in all respects to the apparatus associated with the left hand end of section E—Q.

40 Before explaining the operation of the system as a whole it should be pointed out that the trackway apparatus herein shown and described is intended for co-operation with train carried governing apparatus in the following manner: When the train is on a portion of track which is supplied with track circuit current and with local current of normal relative polarity, the governing apparatus allows the train to proceed at a high speed, as 65 miles per hour; when the train is on a portion of track supplied with track circuit current and also with local current, the relative polarity of either of which is reversed, the governing apparatus allows the train to proceed at an intermediate speed such as 35 miles per hour; and if the train enters a stretch of track to which the supply of either track circuit current or local current is for any reason interrupted, the governing apparatus prevents the train from proceeding at speeds in excess of some low speed as 15 miles per hour.

In at least one form of train governing apparatus suggested for this purpose the governing mechanism is controlled by the

current or currents in the track rails through the medium of receiving appliances carried on the front of the train. It is evident that with apparatus of this character the source of track circuit current must at all times be connected with the rails in advance of the train or the wheels and axles of the train will shunt the track circuit current away from the receiving apparatus and the governing apparatus will then impose a low speed limitation upon the train irrespective of traffic conditions.

As shown in the drawing the parts are all in the positions corresponding to normal conditions, that is, the stretch of track is unoccupied and all signals display a stop indication. I will now assume that the despatcher wishes to allow a train, moving from right to left, to pass through the portion of track shown in the drawing. Relay W^0 is energized, the circuit for relay W^2 is closed and relay W^2 is therefore energized in the normal direction. Now if the despatcher closes contact 153—155 of selector X^0 , the relay I^{13} is energized and is maintained in this condition until a subsequent energization of relay L^{13} opens the retaining circuit for relay I^{13} through back contact 161 of relay L^{13} . The energization of relay I^{13} closes the circuit for relay G^2 which then becomes energized. At the same time the opening of back contact 41 of relay I^{13} opens the circuit of relay W^0 which becomes de-energized since the branch for this circuit over a front contact of relay K^{11} is open, K^{11} being de-energized. The de-energization of relay W^0 de-energizes in turn, relays W^1 and W^3 . Relay W^{11} is de-energized by the opening of back contact 195 of relay G^2 , and also by the opening of back contact 196 of relay I^{13} . The energization of relay G^2 opens, at its back contact 246, the circuit for stop lamp 4 of signal S^2 and closes at front contact 246, the circuit for proceed lamp 6 of signal S^2 which becomes lighted thus causing signal S^2 to display a proceed indication. It is, then, clear that in causing signal S^2 to display a proceed indication to allow traffic to pass from right to left, the despatcher has caused all the opposing line relays between signal S^2 and the next signal in advance, to become de-energized.

As the train enters section E—Q, accepting signal S^2 , track relays R^2 and R^{11} are de-energized and stick relay K^2 and repeater relay P^{11} are energized. As a result the winding 8 of track transformer T^2 is de-energized and the shunt around impedance 14 of relay R^2 is opened. Simultaneously, track transformer T^{11} is energized and relay R^{11} is disconnected from the rails. Line relays W^2 and W^{11} and slow acting relays G^2 and G^{11} are now de-energized thus causing signal S^2 to display

a stop indication for protecting the train, which now occupies section E—Q, from a following train. Section E—Q is provided with local current of normal relative polarity and with track circuit current from transformers N^E and T^{11} , respectively, and the train is therefore allowed to pass through the section at high speed. As the train enters section D—E track relays R^4 and R^9 are de-energized but no other change is made in the apparatus since relay W^9 is already de-energized thus making it impossible to pick up relay K^9 . Track circuit current is supplied to the rails of the section by transformer T^9 and local current of normal relative polarity is supplied to the section by winding 18 of local transformer N^D and the train is therefore allowed to proceed through the section at high speed.

As the rear of the train leaves section E—Q, track circuit current from transformer T^{11} energizes relay R^2 which closes its front contacts, de-energizing relays K^2 and P^{11} , and thereby energizing track transformer T^2 , closing the shunt around impedance 14 associated with track relay R^2 , de-energizing track transformer T^{11} and reconnecting track relay R^{11} with the rails of the section. This relay R^{11} thereupon becomes energized. Relay W^{11} does not become energized however, because its circuit is broken at back contact 196 of relay I^{13} .

Track relays R^7 and R^6 are de-energized as soon as the train enters section C—D, thus energizing relay K^6 and de-energizing relay W^6 . Relay W^7 is already de-energized and relay K^7 therefore can not pick up. As the rear of the train passes out of section D—E, track relays R^9 and R^4 are energized, thus completing the circuit for relay W^2 . But relay W^6 , which controls the polarity of this current supplied to this relay, is de-energized and the relay W^2 is therefore energized in the reverse direction. Furthermore, relay I^{13} is still energized and relay G^2 is consequently energized thus causing signal S^2 to display a caution indication. The operation of the apparatus as the train passes through section B—C will be readily understood from the foregoing and is similar in all respects to the operation of the apparatus associated with section C—D. As the train passes out of section C—D, the energization of track relays R^7 and R^6 de-energizes relay K^6 and causes relay W^6 to become energized, thereby energizing relay W^2 in the normal direction and causing signal S^2 to display a proceed indication.

Assuming that signal S^{12} is at stop, as shown in the drawing, the entrance of the train, which has been permitted to pass through section B—C at 65 miles per hour into section A—B causes track relays R^{10}

and R^3 to become de-energized, thus energizing relays K^{10} and P^3 and transformer T^3 . This operation also disconnects track relay R^3 from the rails of the section, de-energizes transformer T^{10} , and opens the shunt around impedance 14 associated with relay R^{10} .

Track circuit current is supplied to the rails of the section by transformer T^3 and since relay I^3 is de-energized, relay G^2 is also de-energized and the rails of section A—B are supplied with local current of reverse relative polarity between impedances 11 and 13 but not between impedances 10 and 11. The speed of the train is therefore reduced, by the governing apparatus, to 35 miles per hour as soon as it enters section A—B under these conditions. The train may then proceed at 35 miles per hour or less, as far as impedance 11 in section A—B beyond which it may only proceed at speeds below 15 miles per hour.

If the dispatcher closes contact 153—155 of selector X^A , the apparatus located at point A will operate in the same manner as that located at point F, and signal S^{12} will display a proceed indication. Under these conditions, relay G^{12} will of course, be energized, local current of normal relative polarity will be supplied to the rails of section A—B throughout the section and the train will be allowed to proceed at high speed.

I will now assume that a train moving from right to left occupies section D—E. As explained before, relays R^9 , R^4 , K^9 , P^4 , W^2 and G^2 will be de-energized as a result of the presence of this train, and signal S^2 will be at stop. Now if a following train should attempt to enter the stretch of track shown in the drawing, the governing apparatus would reduce its speed to 35 miles per hour at the right hand end of the section to the right of Q, and would further reduce the speed of the train to 15 miles per hour at impedance 11 immediately to the right of Q as explained in connection with section A—B. If the train should pass point Q, the low speed limitation would still be enforced because the local circuit is open at front contact 192 of track relay R^4 and at front contact 189 of relay K^2 which can not pick up due to the de-energization of relay G^2 . In addition, the train would be deprived of track circuit current after passing the point of connection of transformer T^2 , by the shunting effect of its own wheels and axles, because the energization of transformer T^{11} requires the energization of relay K^2 which we have seen can not occur under these conditions.

I will now assume that a train moving from right to left occupies section B—C. It is plain that a following train, passing through section D—E at high speed, will be reduced to 35 miles per hour at point D, by

the reversal of polarity of local current resulting from the de-energization of line relay W^o . Similar protection against following trains is afforded by apparatus associated with the remaining sections and will be readily understood from the foregoing.

If the route is set up for traffic from right to left, that is, if signal S^o is at proceed, the de-energization of all the opposing line relays W , resulting from the accepting of the signal by a train moving in the direction in which the signal governs, imposes restricted speed limitations upon all traffic moving in a direction opposite to the route set up.

Assuming that the route is set up for traffic from right to left, that the stretch of track shown in the drawing is unoccupied and that the despatcher wishes to allow train movements from left to right through the portion of track to the right of signal S^{11} , he momentarily closes contact 153-154 of selector X^o thereby closing the circuit for relay L^{12} which becomes energized. The opening of back contact 161 of relay L^{12} de-energizes relay I^{12} and thereby de-energizing relay G^o . This changes the indications of signal S^o from proceed to stop. The closing of back contact 195 of relay G^o and the closing of back contact 196 of relay I^{12} allows relay W^{11} to pick up and the closing of back contact 41 of relay I^{12} closes the branch for relay W^o . Now if the despatcher closes contact 153-155 of selector X^o the route will be set up for traffic from left to right in a manner entirely analogous to that described in explaining the operation of the apparatus for movements from left to right. It is of course understood that the apparatus to the left of point E is responsive to manipulations of a selector X not shown in the drawing in exactly the same manner that the apparatus to the right of selector X^o is responsive to manipulations of that selector.

In the light of the preceding description, it is clear that the despatcher controls not only the indication displayed by the signals but also the local circuits for the portions of track governed by those signals. For example, with the apparatus in the position shown in the drawing signal S^o displays a stop indication and a train attempting to pass this signal is immediately brought to a low speed by the interruption of the local current since one local circuit for section $E-Q$ is broken at front contact 187 of relay K^o , which can not pick up because of the de-energized condition of relay G^o , and the other local circuit for this section is broken at front contact 183 of relay K^{11} . As has been pointed out hereinbefore this low speed limitation is imposed upon the train throughout the stretch of track shown in the drawing. If, however, the despatcher causes relay I^{12} to become energized, thus energiz-

ing relay G^o , a train moving toward the left into section $E-Q$ will pick up relay K^o and will be supplied with local current. The despatcher therefore has absolute control of the movements of trains through the stretch of track illustrated in the drawings.

Although I have herein shown and described only one form and arrangement of railway traffic controlling apparatus embodying my invention, it is understood that various changes and modifications may be made therein within the scope of the appended claims without departing from the spirit and scope of my invention.

Having thus described my invention, what I claim is:

1. In combination, a stretch of railway track, a selector comprising two contacts and controlled from a distant point, an electro-responsive device for controlling traffic through said stretch, a circuit for said device including one of said contacts, a second electro-responsive device controlled by said second contact, a third contact controlled by said second device and an auxiliary circuit for said first device including said third contact.

2. In combination, a stretch of railway track, a relay for governing traffic through said stretch, a selector controlled from a distant point and comprising two contacts, a pick-up circuit for said relay controlled by the first contact on said selector, an auxiliary relay controlled by the second contact on said selector, and a retaining circuit for said first relay including a contact on said auxiliary relay.

3. In combination, a stretch of railway track, a relay for governing traffic through said stretch, a selector controlled from a distant point and comprising two contacts, a pick-up circuit for said relay controlled by the first contact on said selector, an auxiliary relay controlled by the second contact on said selector, and a retaining circuit for said first relay including a front contact thereon and a back contact on said auxiliary relay.

4. In combination, a stretch of railway track, a relay responsive to traffic conditions in said stretch, an electro-responsive device, means controlled by said relay and operated from a distant point for moving said device to an operative position, means for retaining said device in its operative position, traffic governing apparatus controlled by said device, and means operated from a distant point for rendering said retaining means ineffective.

5. In combination, a stretch of railway track, a device for governing traffic over said stretch, a relay for controlling said device, a second relay for controlling said first relay, two normally open contacts, means controlled from a distant point for momentarily closing one contact or the other at will, and pick-up

- circuits for said two relays including said two contacts, respectively. 65
6. In combination, a stretch of railway track, a device for governing traffic over said stretch, a relay for controlling said device, a second relay for controlling said first relay, two normally open contacts, means controlled from a distant point for momentarily closing one contact or the other at will, pick-up circuits for said relays including said two contacts, respectively, and a retaining circuit for said first relay excluding the associated contact but including a contact controlled by said second relay. 70
- 15 7. In combination, a stretch of railway track, two normally open contacts, means operated from a distant point for momentarily closing either of said contacts at will, means controlled by one of said contacts for supplying a train governing current to said stretch, retaining means for continuing such supply after the opening of said contact, and means controlled by said second contact for rendering said retaining means ineffective. 80
- 25 8. In combination, a stretch of railway track, a source of train governing current, two normally open contacts, means operated from a distant point for momentarily closing either of said contacts, means controlled by one of said contacts for connecting said source with the rails of the section, and means controlled by the other said contact for interrupting said connection. 85
- 35 9. In combination, a stretch of railway track, a source of train controlling current, two normally open contacts, means operated from a distant point for momentarily closing either of said contacts, means controlled by one of said contacts for connecting said source with the rails of the section, retaining means for subsequently maintaining said connection after the said contact has re-opened, and means controlled by the remaining said contact for rendering such retaining means ineffective. 90
- 45 10. In combination, a stretch of railway track, a source of train controlling current, two normally open contacts, means operated from a distant point for momentarily closing either of said contacts, means controlled by one of said contacts for connecting said source with the rails of the section, retaining means responsive to traffic conditions in said section for subsequently maintaining said connection after the said contact has re-opened, and means controlled by the remaining said contact for rendering such retaining means ineffective. 95
- 55 11. In combination, a section of railway track, a source of train controlling current, a repeater relay, means controlled by said repeater relay and responsive to traffic conditions in said section for connecting said source with the rails in parallel of such sec- 100
- tion, a second relay for operating said repeater relay, selecting means controlled from a distant point for energizing said second relay, means for subsequently continuing said energization, and separate means controlled by said selecting means for de-energizing said second relay. 105
12. In combination, a forward and a rear section of railway track, a source of train controlling current, a repeater relay, a track relay for said forward section, means controlled by said repeater relay and said track relay for connecting said source with the rails in parallel of said rear section, and selecting means operated from a distant point for controlling said repeater relay. 110
13. In combination, a section of railway track, two normally open contacts, means operated from a distant point for momentarily closing either of said contacts at will, a relay, a pick-up circuit for said relay including one of said contacts, a second relay, a retaining circuit for said first relay including a contact on said second relay, and a train controlling circuit for said section controlled by said first relay. 115
14. In combination, a portion of railway track, normally ineffective means for supplying train governing current to the rails of said portion, a selector located adjacent said portion of track and controlled from a distant point, and apparatus controlled by said selector and by traffic conditions in advance of said portion of track for rendering said means effective to supply train governing current to the rails of said section. 120
15. In combination, a portion of railway track, normally ineffective means for supplying train governing current to the rails of said portion, a selector located adjacent said portion of track and controlled from a distant point, a track relay associated with a section in advance of said portion of track, and apparatus controlled by said selector and by said track relay for rendering said means effective to supply train governing current to the rails of said section. 125
16. In combination, a section of railway track, a relay, apparatus controlled by said relay for supplying alternating train governing current of one relative polarity to the rails of said section in multiple from the entrance to the exit ends of said stretch, or for supplying alternating train governing current of the other relative polarity to the rails of said section in multiple from the entrance end to an intermediate point in the section, a selector located adjacent said section and controlled from a distant point, and means for controlling said relay by said selector. 130
17. In combination, a section of railway track, a relay, apparatus controlled by said relay for supplying alternating train gov-

erning current of one relative polarity to the rails of said section in multiple from the entrance to the exit ends of said stretch or for supplying alternating train governing current of the other relative polarity to the rails of said section in multiple from the entrance end to an intermediate point in the

section, a selector located adjacent said section and controlled from a distant point, and means for controlling said relay by said selector and by traffic conditions in advance of said section. 10

In testimony whereof I affix my signature.
RONALD A. McCANN.
